UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A HANDLE FOR SPOONS, &c.

SPECIFICATION forming part of Design No. 24,954, dated December 10, 1895.

Application filed October 19, 1895. Serial No. 566,258. Term of patent 14 years.

To all whom it may concern:

Be it known that I, AUSTIN F. JACKSON, a citizen of the United States, residing at Taunton, in the county of Bristol and State of Massachusetts, have invented and produced 5 new and original Design for Handles of Spoons, Forks, &c., of which the following is a specification, reference being had to the accompanying drawings, showing a part thereof.

Figure 1 is a view of the front face of a spoon bearing my design, showing in dotted lines its application to a fork. Fig. 1^a is a cross-section through line *a a*. Fig. 1^b is a cross-section through line *b b*. Fig. 1^c is a 5 view of the bowl broken away through the middle transversely, and Fig. 2 is a view of the back face of a spoon bearing my design.

The leading feature of the front face of my design consists of three concave longitudinal flutes in connection with ornamental scroll-work, (see Figs. 1, 1^a, and 1^b.) the middle concave flute *d d'* being the broadest and the side flutes *e* and *e'* being along the margin and narrower. Near the middle of the handle, 5 between the flutes *d' e' e'* and *d e e*, is a convex shield-like surface *i*, flanked on each side with doubled marginal scrolls *jj*. Surmounting the broad end of the handle is a scroll-and-ball terminal ornamentation *h*, and centrally 10 beneath the same are two eagle-heads *g g*,

and below them along the edges are two scroll-and-ball ornamentations *ff*. At the junction of the shank with the bowl are three rows of bead-like ornaments *k*, while the portion of the bowl at their end is corrugated or fluted 35 as seen at *l*.

The leading feature of the back is a central display of flowers and foliage spread upon the broad portion of the handle, with scrolled borders *m' m'* on the sides, a scroll-and-ball 40 ornament *h'* at the top, and doubled scrolls *j' j'* at the bottom. The shank is convex on its face with a marginal bead at each edge, and a griffin's head *k'*, with scrolls around it, is placed at the junction of the shank and 45 the bowl.

What I claim is—

1. In the design for the handle of a spoon or similar article, the front face as herein shown and described. 50
2. In a design for the handle of a spoon or similar article, the back face as herein shown and described.
3. The design for the handle of a spoon or similar article, as herein shown and described. 55

AUSTIN F. JACKSON.
